UNITED STATES PATENT OFFICE.

WOJCIECH KOZANSKI, OF LODZ, RUSSIA.

TROUSERS-STRETCHER.

SPECIFICATION forming part of Letters Patent No. 642,338, dated January 30, 1900.

Application filed July 24, 1899. Serial No. 724,937. (No model.)

To all whom it may concern:

Be it known that I, WOJCIECH KOZANSKI, a subject of the Czar of Russia, and a resident of the town of Lodz, in the Province of Poland, 5 Russia, have invented certain new and useful Improvements in Trousers-Stretchers, of which the following is a specification.

The object of the present invention is an appliance for stretching trousers whereby 10 wrinkles may be removed therefrom, the cloth cleaned or washed, and the effect of creasing produced, as if ironed.

The invention is shown in the accompanying drawing, which forms a part of this application, in which the figure is a plan view of the appliance.

Referring to the drawing, it will be seen that the device consists of two flat pieces of wood *a a'*, having rounded portions near the 20 ends and somewhat wider at one end than at the other. The adjacent edges of these pieces are connected by means of toggles or links *b b'*, pivoted in pairs at one end to the pieces *a a'* and at the other end to internally-threaded 25 collars *c c'*, respectively. These collars are mounted on a right and left hand threaded spindle or rod *d*, the right-hand-threaded portion passing through one of the collars and the left-hand-threaded portion passing through 30 the other, thus effecting the movement in opposite directions of the collars upon the spindle being turned. Suitable recesses are cut in the boards to allow for the movement of the toggles.

35 Mounted on the spindle *d* at a point intermediate the collars *c c'* is a coupling *e*, which

is perforated for the passage of the spindle, so that the latter may move freely therein, either to rotate or to move longitudinally. This coupling has extending therefrom, at 40 right angles to the spindle, arms *f*, which project into cavities or recesses formed therefor in the boards, and thereby prevent longitudinal displacement of said boards.

To facilitate the use of the appliance when 45 it is desired to clean trousers and to prevent the cloth from coming in contact with the spindle and toggles, I provide a tin-plate protector or shield, which can be secured to the boards in any suitable manner which will 50 permit the lateral movement of said boards, such plate being shown by dotted lines in the drawing.

Having thus described my invention, what I claim as new, and desire to obtain by Letters 55 Patent, is—

In a trousers-stretcher, the combination of flat side pieces, with toggles pivoted to said pieces and to collars, a right and left hand threaded spindle working in said collars and 60 a coupling perforated to receive the spindle and provided with lateral arms, said side pieces being recessed to receive said toggles and said lateral arms, substantially as set forth.

65 In testimony that I claim the foregoing as my invention I have signed my name in presence of two subscribing witnesses.

WOJCIECH KOZANSKI. [L. S.]
